(57) **CLAIM**

The ornamental design for a cooking utensil, as shown and described.

DESCRIPTION

FIG. 1 is a perspective view of the cooking utensil showing our new design;

FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is a bottom view thereof.

The cooking utensil is shown with symbolic breaks in its length. The appearance of any portion of the article between the jagged dot-dash break lines forms no part of the claimed design. The dashed broken lines depict portions of the cooking utensil and form no part of the claimed design. The dash-dot lines represent the bounds of the claimed design and form no part thereof.
